LUGGAGE RACK

John A. Bott, 931 Lake Shore Drive,
Grosse Pointe Shores, Mich. 48236

Original design application Oct. 27, 1967, Ser. No. 9,517,
now Patent No. 212,186, dated Sept. 10, 1968. Divided
and this application Aug. 5, 1968, Ser. No. 13,382

Term of patent 14 years

Int. Cl. D12—14

U.S. Cl. D14—27

FIGURE 1 is a perspective view of a luggage rack, showing my new design;

FIGURE 2 is an enlarged perspective view of a portion thereof; and

FIGURES 3 and 4 are sectional views taken along the lines 3—3 and 4—4, respectively, of FIGURE 2.

The portion of a motor vehicle shown in broken lines in FIGURE 1 is included for illustration purposes only.

This application is a division of my copending application Ser. No. D. 9,517, filed Oct. 27, 1967, now Patent No. D. 212,186.

I claim:

The ornamental design for a luggage rack, substantially as shown and described.
